[57] CLAIM

The ornamental design for a vehicle wheel front face, as
shown and described.

DESCRIPTION

FIG. 1 is a front perspective view of a vehicle wheel
front face; and,

FIG. 2 is a front elevational view thereof.

The broken lines shown in FIG. 1 of the drawings are
for illustrative purposes only and the subject matter
depicted thereby constitutes no part of the claimed
design.

FIG. 1

FIG. 2
